MEANS FOR SYNCHRONIZING HYDRAULIC RAMS

Filed June 20, 1938

UNITED STATES PATENT OFFICE

2,243,716

MEANS FOR SYNCHRONIZING HYDRAULIC RAMS

Kenneth C. Monroe, Hudson, Mass., assignor to
 The La Pointe Machine Tool Company, Hudson,
 Mass., a corporation of Maine

Application June 20, 1938, Serial No. 214,755

5 Claims. (Cl. 60—52)

This invention relates to duplex hydraulic machine tools, such as duplex broaching machines, and relates particularly to machines in which hydraulic rams move vertically in the machines and move simultaneously in opposite directions.

In the operation of such machines, it is customary to force oil back and forth between the lower ends of the ram cylinders during the alternate movements of the rams in opposite directions, and it is necessary that a full supply of oil be present in these cross-connected cylinders in order to obtain satisfactory and efficient operation. Otherwise, one ram may complete its downward or working stroke before the other ram has been fully raised and this failure to completely raise the idle ram may prevent removal and replacement of the work or may produce other undesirable results.

It is the object of my invention to provide improved means for automatically maintaining a full supply of oil in the cross-connected portions of a duplex hydraulic machine, and for promptly replacing any oil which may be lost in operation or while the machine stands idle.

My invention further relates to arrangements and combinations of parts which will be hereinafter described and more particularly pointed out in the appended claims.

A preferred form of the invention is shown in the drawing which is a diagrammatic view, partly in section, of duplex hydraulic mechanism embodying my improvements.

Referring to the drawing, I have shown portions of a duplex broaching machine, including slides 10 and 11 connected to rams or pistons 12 and 13 slidable in cylinders 14 and 15. A pump P is connected by pipes 20 and 21 to the upper ends of the cylinders 14 and 15 respectively, and the lower ends of the cylinders are cross connected through a pipe 22, back-pressure valve 23, pipe 24, relief valve 25, pipe 26, back-pressure valve 27 and pipe 28.

The pump P is preferably of the variable discharge reversible type, such as is shown for instance in West Patent No. 1,722,832, and the direction and rate of discharge is controlled by a lever 30 pivoted at 31 and connected by a link 32 to a rack bar 33 which engages a pinion 34 in the pump P.

By moving the lever 30 and rack bar 33 in either direction from the neutral position shown in the drawing, the pump P may be caused to discharge at any desired rate into the pipe 20 or into the pipe 21, as selected. The lever 30

may be operated manually or by any suitable automatic devices.

An auxiliary pump P' is also provided, which is connected through a pipe 40, relief valve 41 and pipe 42 to supply oil under pressure for operating fixtures, shifting valves and effecting other desired results, the pump P' being continuously operated at constant speed and the excess oil being returned to storage from the relief valve 41 through a pipe 43.

The parts thus far described are or may be of the usual type and construction and in themselves form no part of my present invention.

In the machine shown, it is customary to stop the machine with the right-hand slide 11 and ram 13 in lowered position, and the left-hand slide 10 and ram 12 in raised position. These rams and slides in modern broaching machines have attained large size and extremely heavy weight, and it is found that, if such a machine is left idle for a considerable period, the raised slide and ram will drift downward by slow leakage of oil past the piston 12 or by reason of temperature changes. Such lowered position of the ram 10 is indicated in full lines in the drawing, while the fully raised and desired position is indicated in broken lines.

I will now describe my improved construction by which the raised slide and ram are maintained in normal position or are quickly restored thereto. For this purpose I connect the relief valve 41 through a branch pipe 50, valve 51, pipe 52, valve 53, pipe 54 and check valve 55 to the pipe 22, previously described, which connects into the lower end of the cylinder 14.

The valve 51 is spring operated and is open only when a cam plate 60 on the slide 11 engages the valve plunger 61. Such engagement takes place only when the slide 11 is in its extreme lowered position.

The valve 53 is also spring operated but is normally open except when closed by engagement of a cam plate 62 on the slide 10 with the plunger 63 of the valve, which engagement takes place only when the slide 10 is in fully raised position.

I also provide a by-pass 70 from the pipe 20 to storage through a valve 71. This valve 71 is spring-operated and is controlled by a cam 72 engaging the valve plunger 73 and attached to and movable with the lever 30. These parts are so positioned that the valve 71 is open when the lever 30 is in neutral or mid-position, but is positively closed if the lever 30 and cam 72 are moved in either direction from mid-position.

Having described the details of construction of my improved synchronizing means, I will now describe the operation thereof.

Assuming that the machine has been idle for some time and that the slide 10 and ram 12 have drifted downward to the position shown in full lines in the drawing, the operator in starting up the machine will first start the motors for the pumps P and P'. The pump P, being in neutral position, will deliver no oil and will produce no effect, but the pump P' will deliver oil under pressure to the relief valve 41 and pipes 42 and 50.

As the slide 11 is in its lowered position, the valve 51 will be open, and as the slide 10 is not in extreme raised position, the valve 53 will be open. Consequently, oil under pressure from the pump P' will be delivered through the check valve 55 and pipe 22 into the lower end of the cylinder 14 and will force the ram 12 and slide 10 upward until the slide 10 reaches its fully raised position and closes the valve 53.

The parts are thus placed in normal position for satisfactory operation, and this same action will take place at any time during the operation of the machine if the slide 10 fails to move to its fully raised position.

The check valve 55 prevents escape of oil from the cross connection between the cylinders 14 and 15 during normal operation of the machine, 30 and the back-pressure valve 23 prevents escape of oil through the cross connection to the cylinder 15 during the restoration of the ram 12 and slide 10 to fully raised position, the relief valve 41 being set for lower pressure than the back-pressure valve 23.

It will be obvious that the oil which has leaked past and above the piston 12 must be ejected from the cylinder 14 as the piston 12 is raised, but this oil cannot be forced into or through the pump P when the latter is in neutral position. The by-pass 70 becomes operative under these conditions, and the excess oil in the upper part of the cylinder 14 is forced out to storage through the pipe 70 and valve 71, which valve is then open, as the lever 30 is in mid-position and the pump P is in neutral.

As soon, however, as the pump P is rendered operative by shifting the lever 30 in either direction, the valve 71 closes, so that no oil can escape through the by-pass 70 while the machine is in operation.

One great advantage of the described stabilizing means is that it requires no attention from the operator but becomes automatically effective to restore the parts to normal operating relation as soon as the pump P' is started. The stabilizing means also acts without attention or supervision to restore the normal relation of the rams and slides during the operation of the machine, if such normal relation is disturbed for any cause such as leakage or change in temperature. One outstanding advantage of my improved stabilizing means is its extreme simplicity. No adjustments of any kind are required and the invention works equally well, whether the machine is operated idle or under load.

Having thus described my invention and the advantages thereof, I do not wish to be limited to the details herein disclosed, otherwise than as set forth in the claims, but what I claim is:

1. In a duplex hydraulic machine tool having two main cylinders cross-connected together at one end of each, a pump selectively operable

to supply oil under pressure to the other end of one or the other of said cylinders, and slides connected to pistons in said cylinders and thereby movable simultaneously but oppositely vertically, that improvement which consists in providing an additional supply of oil under constant pressure, a passage to admit said oil to the cross-connected end of a first cylinder, a first valve in said passage which is open unless the piston and slide associated with said first cylinder is in extreme raised position, a second valve in said passage in series with said first valve and which second valve is closed unless the piston and slide associated with the second cylinder are in extreme lowered position, and a relief valve in the cross-connection which is set to open only at a pressure in excess of the constant pressure in said passage.

2. The combination in a machine tool as set forth in claim 1, in which a reversible discharge pump provides the oil to actuate said pistons and slides, and in which a discharge valve is provided for escape to atmosphere of surplus oil above the piston in said first cylinder when said piston is below its fully raised position at the time the piston in the second cylinder is in its fully lowered position, but said discharge valve being open only when said pump is in no-discharge position and being automatically closed whenever said pump is supplying oil to either main cylinder.

3. The combination in a machine tool as set forth in claim 1 in which said first valve is closed and said second valve is opened by devices on the slides when moved to their extreme raised and extreme lowered positions, respectively.

4. In a duplex hydraulic machine tool having two main cylinders cross-connected together at one end of each, a pump selectively operable to supply oil under pressure to the other end of one or the other of said cylinders, and slides connected to pistons in said cylinders and thereby movable simultaneously but oppositely vertically, in combination, separate means to supply make-up oil under constant pressure to one of said cross-connected cylinders, automatic means to prevent such make-up oil entering said cylinder unless the piston in said cylinder is below its upper limit of travel and the piston in the other cylinder is at its lower limit of travel, and a relief valve in the cross-connection which is set to open only at a pressure in excess of the pressure of said make-up oil.

5. In a duplex hydraulic machine tool having two main cylinders cross-connected together at one end of each, a pump selectively operable to supply oil under pressure to the other end of one or the other of said cylinders, and slides connected to pistons in said cylinders and thereby movable simultaneously but oppositely vertically, in combination, separate means to supply make-up oil under constant pressure to one of said cross-connected cylinders when the piston in said cylinder is below its upper limit of travel and the piston in the other cylinder is at its lower limit of travel, a device to freely vent said one of said cross-connected cylinders at the end opposite to which said separate means is supplying make-up oil when said pump is in no-discharge position and a relief valve in the cross-connection which is set to open only at a pressure in excess of the pressure of said make-up oil.

KENNETH C. MONROE.
